UNITED STATES PATENT OFFICE.

FREDERICK S. CHANONHOUSE, OF MALDEN, MASSACHUSETTS, ASSIGNOR TO JOHN L. WHITING-J. J. ADAMS CO., OF BOSTON, MASSACHUSETTS, A CORPORATION OF MASSACHUSETTS.

BRUSH AND METHOD OF MAKING THE SAME.

Application filed June 1, 1922. Serial No. 565,112.

To all whom it may concern:

Be it known that I, FREDERICK S. CHANONHOUSE, a citizen of the United States of America, and resident of Malden, county of Middlesex, State of Massachusetts, have invented certain new and useful Improvements in Brushes and Methods of Making the Same, of which the following is a specification.

10 This invention relates to the construction of brushes, more particularly such as are made of bristles, and the invention is designed to provide a secure method of holding the bristles in a bristle holder and at 15 the same time satisfactorily uniting the bristle holder with the brush back.

Heretofore it has been repeatedly proposed to construct brushes by setting a tuft or knot of bristles in a cup-like holder and 20 then fixing this holder to the brush back, but the difficulty with all of such brushes was that the bristles were not held properly and the brush in a short time went to pieces. I have discovered that the reason for the 25 prior failures was the absence of co-operation between the means relied upon to hold the bristles in the bristle holder on the one hand, and the means whereby the bristle holder was fastened to the brush on the 30 other, but that co-operation between these two means will, on the other hand, produce a brush which is practically indestructible and which will hold the bristles until the brush is worn out.

35 My invention is illustrated in the accompanying drawings, in which Figs. 1 to 7 represent, diagrammatically, various stages in the operation of producing the brush.

In the drawings *a* represents a knot of 40 bristles or hair or similar material which is inserted in any appropriate manner in the ferrule or eyelet *b*. This eyelet *b* is preferably annealed, is open at both ends and is provided with a permanent flange *c* at its 45 wider end. From the flange *c* the eyelet tapers slightly, say with a six degree taper, toward the rear. The eyelet is described in detail and in this art the use of such eyelets is, I believe, wholly new. After the knot of 50 bristles has been inserted in one of these eyelets so as to substantially fill the same and to fit snugly therein at the butt ends of the bristles, the eyelet is drawn back to a slight extent as indicated, for instance, in Fig. 2,

and the end of the knot of bristles is caused 55 to be permeated with rubber or a similar substance. The eyelet is then drawn back on the knot of bristles to a position corresponding approximately to that shown in Fig. 3 or in other words until its smaller 60 end closely approaches but does not reach the ends of the bristles. The thus prepared tufts carrying the ferrules or eyelets are exposed to a vulcanizing treatment.

A metal brush back *d* is provided with 65 suitable apertures *e* for the reception of such tufts of bristles, whereupon the brush back *d* is placed in a suitable press, and the individual tufts inserted in the apertures in the manner shown in Fig. 2 of the drawing, and 70 thereupon dies *f*, *g* become operative upon the eyelet or ferrule *b*. As the dies approach each other it will be observed that their first action will be to constrict the narrower end of the eyelets as illustrated in Fig. 4, thereby 75 compressing the vulcanized rubber in which the knots of bristles are embedded at this point. When the resistance of the compressed bristles is such that they have reached their maximum amount of compression, the sides of the eyelet begin to yield, bulging outwardly as indicated diagrammatically in Fig. 4 and being finally pressed down as shown in Fig. 5, to form a flange *h* 80 which engages the brush back *d* on the surface opposite to this engaged by the flange *c*.

It will be observed that in making brushes in this way, it will be almost impossible that the same number of bristles shall be at any 85 one time contained in the eyelets *b* and that 90 there will be considerable variations due to this fact. If the eyelets are so filled with bristles and rubber that they offer resistance to the action of the dies at an early stage, the flange *h* will begin to form shortly after the 95 dies begin to approach each other and will be larger and wider than in the case where there are fewer bristles in the eyelet. In either case, however, the flange *h* co-operating with the flange *c* will form a secure and 100 permanent method of attachment between the eyelet *b* and the metal brush back *d* and in either case the upper or contracted end of the eyelets *b* will always, irrespective of the number of bristles contained therein, 105 represent the same maximum contraction with respect to the resistance offered by the bristles. In other words, the resultant ca-

pacity of retaining the bristles in the ferrule will be alike, no matter to what extent the eyelet was filled with bristles in the first instance.

5 It will also be observed that the projecting butt ends of the bristles embedded in vulcanized rubber, are wider at the end of the process than the narrow end of the ferrule, whereby a most secure and substantially indestructible means for holding the bristles in the brush is brought about. The eyelets can be made in almost any desired size or shape, although they are preferably made round. For certain types of brush, however, 10 the eyelet may be oval and the entire brush instead of being composed of a multiplicity of tufts be constituted of one single tuft. It is important and essential that the folds or shoulders constituting the flange *h* are not 15 completely formed in the eyelet until after the eyelet is inserted in the brush back. I am aware that it has been proposed to form eyelets with shoulders intermediate of their ends and then forming the connection between the eyelets and the brush back by bending over the terminal edge of the eyelet 20 as a flange. This is not, however, the method employed in the present invention, which consists essentially in forming or giving 25 final shape to the flange *h* after the eyelets have been brought into assembling position with the brush back, whereby there is achieved not only a perfect union between the eyelets and the brush back but also a 30 substantially perfect manner of retaining the bristles in the eyelets themselves.

The pressure exercised by the dies is such that as the folds *h* and flange *c* are clamped together against the brush back *d*, the ferrule will not turn.

40 Various modifications may be made within the scope of the claims without departing from the nature of my invention.

I claim:

45 1. In a brush, the combination with an eyelet-supporting back, of an annealed metal eyelet open at both ends and having a flange at one end in engagement with that face of the back opposite which the bristles project, said eyelet being tapered from the flanged end gradually and at approximately 50 a 6° angle toward its smaller open end, said eyelet at its smaller end being adapted to receive the butt ends of a knot of bristles, the metal of the tapered sides of said eyelet 55 adjacent the wider end thereof, being deformed to provide a flange in the eyelet at a distance from its end flange to constitute, in co-operation with said flange, a means for fastening the eyelet to the eyelet-supporting back.

60 2. In the art of brush making, that improvement which consists in inserting a tuft of bristles within a slightly tapered eyelet flanged at its larger end and open at both

ends, and then inserting said eyelet in an aperture of a plate in such a manner that the flange of the eyelet contacts with one surface of said plate, then forming a flange-fold on the eyelet at the opposite side of said plate under pressure to fix the eyelet in said plate. 70

3. In the art of brush making, that improvement which consists in inserting a tuft of bristles within an open-ended eyelet 75 flanged at one end, then inserting said eyelet through an aperture of a plate in such a manner that the flange contacts with one surface thereof, constricting said eyelet at its narrower end portion to compress the tuft of 80 bristles within said eyelet and then forming a flange-fold therein upon and in engagement with the opposite side of said plate. 85

4. In the art of brush making, that improvement which consists in inserting a tuft of bristles within an open-ended, slightly tapered eyelet flanged at its larger end, drawing back said eyelet upon said tuft of bristles to expose the butt end thereof and permeating said butt end with rubber, 90 moving the eyelet back until its small end closely approaches but does not reach the ends of said bristles, vulcanizing the permeated tufts, then inserting said eyelet through an aperture of a plate in such a 95 manner that the flange contacts with one surface thereof, constricting said eyelet at its narrower end portion to compress the tuft of bristles within said eyelet and then forming a flange-fold therein upon and in 100 engagement with the opposite side of said plate. 105

5. In the art of brush making, that improvement which consists in inserting a tuft of bristles within an open-ended eyelet flanged at one end, forming the butt end 110 of said tuft of bristles into a coherent mass, then inserting said eyelet through an aperture of a plate in such a manner that the flange contacts with one surface thereof, constricting said eyelet at its narrower end portion to compress the tuft of bristles within said eyelet and then forming a flange-fold therein upon and in engagement with the opposite side of said plate. 115

6. In the art of brush making, that improvement which consists in inserting a tuft of bristles within an open-ended eyelet flanged at one end, then inserting said eyelet through an aperture of a plate in such 120 a manner that the flange contacts with one surface thereof, applying pressure to said eyelet to constrict the same in diameter, to reduce it in axial length and fold it into the form of a flange in engagement with the opposite surface of said plate. 125

7. A brush comprising a supporting plate provided with apertures, bristle-carrying eyelets in said apertures having a flange abutting against the side of the support 130

- where the bristles project and a fold-flange integral with the eyelet and abutting against the opposite side of the support, the two flanges being pressed together sufficiently 5 to prevent rotation of the eyelet in the aperture, said fold-flange possessing the characteristics of a flange formed in the eyelet after the same was inserted in the support, the rear or butt end of the eyelet being 10 tightly compressed against the bristles held by said eyelet.
8. A brush comprising a supporting plate provided with apertures, bristle-carrying eyelets in said apertures having a flange abutting against the side of the support where the bristles project and a fold-flange 15 integral with the eyelet and abutting against the opposite side of the support, the two flanges being pressed together sufficiently to 20 prevent rotation of the eyelet in the aperture, said fold-flange possessing the characteristics of a flange formed in the eyelet after the same was inserted in the support, the rear or butt end of the eyelet being 25 tightly compressed against the bristles held by said eyelet, said bristles being embedded in compressed vulcanized rubber.
9. A brush comprising a supporting plate
- provided with a plurality of apertures, eyelets located in said apertures, outer and 30 inner flanges integral with the latter and clamped against opposite surfaces of said plate to maintain said eyelets in place and against rotation in said apertures, said inner flanges each consisting of a section of 35 the eyelet folded upon itself, and knots of bristles having their ends in said eyelets, the latter tapering toward the butt ends and compressed against the bristles therein.
10. In the art of brush making, the combination of a metal eyelet open at both ends and having a permanent flange at one end, said eyelet tapering from its flange end toward its opposite end, a knot of bristles projecting through and beyond the largest 40 end of said eyelet and having their butt ends adjacent to the smaller end thereof and a second flange located at a distance from said first flange and formed by folding a portion of the metal of said eyelet upon 45 itself, said flanges constituting means for fastening the eyelet and its knot of bristles in a brush back.

In testimony whereof I have hereunto set my hand.

FREDERICK S. CHANONHOUSE.
